(57) **CLAIM**

The ornamental design for a ballpoint pen, as shown and described.

DESCRIPTION

FIG. 1 is a perspective view of a ballpoint pen according to the present invention.

FIG. 2 is a front view of the ballpoint pen of FIG. 1. A rear view is omitted since it is a mirror image of the front view.

FIG. 3 is a left side view of the ballpoint pen of FIG. 1.

FIG. 4 is a right side view of the ballpoint pen of FIG. 1.

FIG. 5 is a top view of the ballpoint pen of FIG. 1.

FIG. 6 is a bottom view of the ballpoint pen of FIG. 1.

FIG. 7 is a top view of the ballpoint pen of FIG. 1 with the cap removed and placed on the opposite end; and,

FIG. 8 is an exploded view of the ballpoint pen of FIG. 1.
